UNITED STATES PATENT OFFICE

ALGERNON B. REESE, OF NEW YORK, N. Y.

OPHTHALMOSCOPE

Application filed March 11, 1930. Serial No. 434,887.

The invention relates to new and useful improvements in an ophthalmoscope, and more particularly to the means for positioning the rotary disc or carrier of the instrument.

The ophthalmoscope includes fixed discs or frame parts having an aperture therethrough and a rotatable disc provided with a clear aperture and with a series of lenses which are adapted to be selectively brought into alignment with the apertures in the stationary discs. There is also a sight opening in the outer disc and the rotatable disc is provided with indicating characters associated with the lenses and the aperture. A yielding device is provided for centering the lens or the aperture in the rotatable disc at the vision apertures through the stationary discs.

An object of the present invention is to provide means whereby the rotatable disc may be positively stopped at a selected aperture through the aid of the hand of the operator.

In the drawings:

Fig. 1 is a front view of an ophthalmoscope;

Fig. 2 is an enlarged view of the same with the front disc broken away to show more fully the construction of the rotatable disc.

Fig. 3 is a side view with parts in section to show the construction of the instrument;

Fig. 4 is an enlarged sectional view on the line 4—4 of Fig. 2;

Fig. 5 is a sectional view on the line 5—5 of Fig. 2, and

Fig. 6 is an enlarged plan view of a segment of the rotatable disc as viewed from the rear.

The invention as shown is applied to an ophthalmoscope which embodies a supporting handle 1 on which is mounted a sleeve 2. Disposed in the sleeve 2 is a lamp 3 in front of which is a lens 4, and at the end of the sleeve is a prism 5. Fixed to the sleeve 2 is an inner stationary member 6 through which is formed an aperture 7 which will be hereinafter referred to as a vision aperture. This inner member 6 carries a hub 8 on which is rotatably mounted a disc 9. Also mounted on the hub 8 is an outer stationary disc 10.

The parts are secured together by means of a screw 11. The outer stationary disc has a portion 12, 12 at the top and bottom which extends over and houses the rotatable disc 9.

The outer stationary disc 10 is provided with an aperture 13 which is in alignment with the aperture 7 and will also be referred to hereinafter as a vision aperture. The rotatable disc 9 is provided with a series of apertures. One of these apertures is preferably left clear, and the other apertures are each provided with a lens. These lenses are of a graded character in two series, one of which may be referred to as a positive series and the other as a negative series. There is an indicating character associated with each aperture. The outer stationary disc 10 is provided with a sight opening 16. The characters with the rotatable disc pass into view in this sight opening. This character indicates the type of aperture which is in alignment with the apertures 7 and 13 through which vision is had. As shown in the drawings, the character zero indicates a clear aperture, and the numerals indicate apertures carrying lenses. A yielding means is provided for centering the apertures carrying the lenses and also a clear aperture in the vision apertures in the stationary discs. This yielding means includes a ball 17 and a leaf spring 18 which is attached to the rear disc. The ball is positioned in an opening in the disc, and the leaf spring bears against the rear face of the rotatable disc 9. This rear face is provided with indentations 19, 19. The ball will be pressed into an indentation, and this will center the selected aperture in the vision apertures in the stationary discs. The rotatable disc is serrated as indicated at 20, and can be readily turned for positioning any one of the apertures in the rotatable disc in alignment with the vision apertures in the stationary discs. Pressure on the rotatable disc will readily move the ball out of the indentation or pocket 19. Thus the disc can be readily turned by the hand of the operator engaging the serrated edge of said rotatable disc. This instrument is used in a dark room for the testing of eyes. Sometimes it is desirable in the beginning of the

examination of the eye, to start with a clear vision aperture, and then work up into the plus or minus, as the condition of the eye indicates. At other times it is desirable to begin the examination with a plus lens and work down through the plus, and possibly into the minus, as the condition of the eye may indicate. In order that the instrument may be quickly and readily, while in a dark room, set at the desired aperture from which the examination is to begin, I have provided a locking pin 21 carried by a bowed spring 22 mounted on headed studs 23, 23, carried by the outer stationary disc 10. There is an opening 24 through this stationary disc. The rotatable disc is provided with an opening 25. The instrument may have only one opening 25, or it may have two or more openings similar to the opening 25. As shown in the drawings, the opening 25 is so positioned in the rotatable disc that when the pin is in the opening 25, the clear vision aperture is in alignment with the apertures 7 and 13 in the stationary discs. The openings 25 are so associated with the apertures that these openings set the instrument for the beginning of an examination. To operate the device, the hand of the operator is pressed against the bowed spring 22, forcing the pin 21 lightly into contact with the rotatable disc 9. When the opening 25 comes beneath the pin it will pass into the opening and positively stop or lock the rotatable disc against further movement in either direction. Thus it is that the operator can, by the aid of the hand, set the disc for the beginning of an examination while still in a dark room.

While I have shown in the drawings, and described in detail, one form of mechanical means for accomplishing the result desired, it will be understood, of course, that other ways may be provided. The one shown is purely for the purpose of illustrating the principle of the invention. While I have shown my invention as applied to an ophthalmoscope, it will be understood that it may be used in connection with other optical instruments of a similar character.

Having thus described the invention, what I claim as new and desire to secure by Letters-Patent, is—

1. An ophthalmoscope comprising stationary discs having vision apertures therethrough, a rotatable disc provided with a series of apertures adapted to be moved into alignment with the vision apertures in the stationary discs, yielding means for centering the apertures in the rotatable disc selectively in alignment with the vision apertures in the stationary discs, and a yieldingly mounted pin carried by one of said stationary discs, said pin being normally out of engagement with the movable disc and manually operated for setting the rotatable disc in a predetermined position relative to the stationary disc.

2. An ophthalmoscope comprising stationary discs having vision apertures therethrough, a rotatable disc provided with a series of apertures adapted to be moved into alignment with the vision apertures in the stationary discs, yielding means for centering the apertures in the rotatable disc selectively in alignment with the vision apertures in the stationary discs, a yieldingly mounted pin normally out of engagement with the rotatable disc carried by one of said stationary discs, and adapted to be forced by hand inwardly into contact with the rotatable disc, said rotatable disc having an opening therethrough for receiving said pin for determining and setting said rotatable disc in a predetermined position relative to the vision apertures in the stationary discs.

3. An ophthalmoscope comprising stationary discs having vision apertures therethrough, a rotatable disc provided with a series of apertures adapted to be moved into alignment with the vision apertures in the stationary discs, yielding means for centering the apertures in the rotatable disc selectively in alignment with the vision apertures in the stationary discs, a bowed spring attached to said outer disc, a pin carried thereby and extending into the opening through said outer disc, said bowed spring normally holding the pin retracted from the rotatable disc, said rotatable disc having an opening therein disposed so as to receive said pin when pressed upon by the hand of the operator for positively determining and setting said rotatable disk in a predetermined position relative to the vision apertures in the stationary discs.

In testimony whereof I affix my signature.
